R. D. MADDOX,
NON-CORROSIVE ATTACHMENT FOR CONTAINERS,
APPLICATION FILED NOV. 26, 1918.

1,383,138.

Patented June 28, 1921.

UNITED STATES PATENT OFFICE.

ROBERT D. MADDOX, OF THE UNITED STATES ARMY.

NON-CORROSIVE ATTACHMENT FOR CONTAINERS.

1,383,138.

Specification of Letters Patent. Patented June 28, 1921.

Application filed November 26, 1918. Serial No. 264,227.

(FILED UNDER THE ACT OF MARCH 3, 1883, 22 STAT. L., 625.)

To all whom it may concern:

Be it known that I, ROBERT D. MADDOX, major, Medical Dept., United States Army, a citizen of the United States, stationed at 5 Washington, District of Columbia, have invented an Improvement in Non-Corrosive Attachments for Containers, of which the following is a specification.

The invention described herein may be 10 used by the Government, or any of its officers or employees in prosecution of work for the Government, or by any other person in the United States, without payment of any royalty thereon.

15 This invention has reference to containers for substances or compounds which are liable to injury by oxidation or from like causes when coming in contact with the material of the container, and has for one of 20 its objects to provide a simply constructed attachment of noncorrosive substance which may be applied to the discharge of the container and protects the contents from contact with material of the container.

25 Another object of the invention is to provide an attachment of a noncorrosive substance including a tubular portion within the discharge of the container and having a lateral flange bearing over the same, and 30 a cap for the discharge having a lining of noncorrosive substance bearing upon the flange portion.

Another object of the invention is to provide a container having tubular discharge, 35 with a lining for the discharge, and a closure cap for the discharge adapted to bear over the lining and engaging the discharge independently of the lining.

With these and other objects in view the 40 invention consists in certain novel features of construction as hereinafter shown and described.

Many containers having discharge openings or nozzles are constructed from material liable to injuriously affect the contents 45 when exposed to the air and in contact with the container material, and to protect the contents of the container from such deterioration the improved attachment which is the 50 subject matter of the present application has been designed.

The attachment may be adapted without material structural change to containers of various forms and to containers for various 55 substances or compounds, but is more par-

ticularly applicable to the collapsible tubes for tooth paste and like substances, and for the purpose of illustration is shown applied to a device of this character, and in the drawings thus employed, 60

Figure 1 is a sectional elevation of a portion of a container including the discharge or nozzle end and its closure cap with the improvement applied.

Fig. 2 is a detached sectional elevation of 65 the attachment in its initial form.

Fig. 3 is a view similar to Fig. 2 illustrating a modification in the construction.

Fig. 4 is a view similar to Fig. 1 illustrating a modification in the construction. 70

The improved attachment comprises a tubular member or shell 10 having a lateral flange 11 at one end as shown in Fig. 2. This is the form in which the shell will be initially produced, and is constructed of non-corrosive material such as "celluloid" or the like. A portion of the body of the container is represented at 12 and the nozzle or discharge at 13, the latter being preferably externally threaded, as represented at 14. 80 The threads do not extend to the top of the nozzle thus leaving a blank space of reduced diameter to receive the down turned outer portion of the flange 11 of the shell. 75

The outer face of the downturned flange 85 portion of the lining is disposed wholly within the reduced portion of the discharge so that no portion of the flange projects beyond the unreduced portion, the object will be hereafter explained.

The interior of the nozzle 13 is also preferably slightly tapered inwardly as shown in Fig. 1 and after the shell 10 is inserted in the nozzle with its flange 11 in place over the outer edge of the nozzle, the inner end 95 of the tubular shell is "swaged" outwardly by a suitable implement to cause the side walls of the shell to closely engage the tapered inner walls of the nozzle and the inner terminal of the shell to be expanded in 100 flange like form over the body of the container at its juncture with the nozzle as shown at 15. By this means the shell is rigidly attached to the nozzle and completely covers and protects the contents of the container material during the discharge. 105

The oxidation occurs just where the paste or other substance passes from the nozzle, and by forming the shell with its flange 11 bearing entirely over the outer rim of the 110

nozzle, the contents of the container will be effectually prevented from contacting with the material of the same.

The cap of the container is represented as 5 a whole at 16 and is threaded to engage the threads 14 of the nozzle. The cap is provided with a lining 17 of noncorrosive substance such as celluloid which contacts with the flange portion 11 of the lining. By 10 this means oxidation is effectually prevented.

The flange or depending rim of the cap thus engages the unreduced portion of the nozzle or discharge, and is held in position independently of the lining member and can 15 be attached to or detached from the receptacle without disturbing the lining.

In Figs. 1 and 2 the shell 10 is shown with the flange 11 formed thereon before the shell is disposed within the nozzle and 20 the inner flange 15 formed by "swaging" the lower edge of the shell by a suitable implement.

The shell 10 may also be constructed as shown in Fig. 3 with the flange 15 upon the 25 shell before the latter is inserted in the nozzle and the flange 11 then swaged over the outer rim of the nozzle to form the same, but this would not constitute a departure

from the principle of the invention or sacrifice any of its advantages.

If preferred the outer face of the nozzle 30 13 may be tapered instead of threaded and the inner face of the cap correspondingly tapered to engage the same, as shown in Fig. 4.

The improved attachment is simple in construction, can be manufactured in quantities and applied to containers already constructed, or applied at the time the containers are made, as may be preferred.

Having thus described the invention what 40 is claimed as new is—

The combination with a container characterized by a tubular discharge portion externally reduced at the outlet end, of a lining for the discharge comprising a tubular member having a lateral bearing flange to engage over the reduced portion with the outer face of the bearing flange disposed wholly within the lines of the unreduced 45 portion, a cap bearing over the discharge portion and engaging the unreduced portion of the discharge, and a lining for the cap having a downturned outer portion engaging over the lateral flange of the lining.

ROBERT D. MADDOX.
